UNITED STATES PATENT OFFICE

110,211

DESIGN FOR A TROPHY

Clarence P. Fisken, Detroit, Mich., assignor to General Motors Corporation, Detroit, Mich., a corporation of Delaware

Application October 18, 1937, Serial No. 72,292

Term of patent 3½ years

To all whom it may concern:

Be it known that I, Clarence P. Fisken, a citizen of the United States and a resident of Detroit, county of Wayne, and State of Michigan, have invented a new, original, and ornamental Design for a Trophy, of which the following is a specification, reference being made to the accompanying drawings, forming a part thereof.

I claim:

The ornamental design for a trophy as shown.

CLARENCE P. FISKEN.
